UNITED STATES PATENT OFFICE

2,353,178

CONTAINER AND METHOD OF MAKING
SAME

George Arlington Moore, New York, N. Y., assignor to Shelimar Products Company, Mount Vernon, Ohio, a corporation of Delaware

Application July 26, 1940, Serial No. 347,583

4 Claims. (Cl. 222—14)

The present invention relates to an improved type of container particularly adapted for the packaging of liquids such as lubricating oil, and has as a principal object the provision of a display container produced from a preformed film or pellicle of a material such as transparent thermoplastic rubber hydrochloride having marginal paper edges laminated to it and an exterior relatively heavy paper board body-imparting reinforcing member provided with a plurality of openings through which the contents of the inner container may be observed.

A further object of the invention is to produce a display container which is of simple construction and of economic manufacture by a method which involves securing an orificed paper board body-imparting member to an inner preformed continuous film of transparent thermoplastic rubber hydrochloride sheet material and heat-sealing together extensions of the rubber hydrochloride film beyond the paper board member, the sealed extensions being folded over and secured to the exterior surface of the paper board member.

Another object of this invention is to provide novel reinforcement to prevent undue distortion of a container in its service.

These and other objects will be evident upon a consideration of the following description of a preferred embodiment of the invention and by reference to the accompanying drawings, in which

Fig. 1 is a fragmentary view of a blank from which the improved container is formed;

Fig. 2 is an end view of the blank shown folded over into an initial stage in the production of the container;

Fig. 3 is a view similar to Fig. 2 and shows a final stage in the formation of the longitudinal seam for the container;

Fig. 4 is a perspective view showing the tubular container resulting from the operation of Fig. 3 with the ends of the container open;

Fig. 5 is a top view of the container shown in Fig. 4 with one end having its end extensions sealed together;

Fig. 6 is a sectional view taken along line 6—6 of Fig. 5; and

Fig. 7 is a perspective view of a finished package constructed in accordance with the invention and provided with a central reinforcing band.

It has been recognized as desirable to package liquid products such as lubricating oil in flexible containers rather than in metallic or other rigid

types of containers heretofore largely employed for this purpose. In addition to the necessity for the flexible container to be liquid-tight, it is desirable that the container afford visibility of its contents. In accordance with the present invention a suitable container providing for visibility is produced from a preformed film or pellicle of a material such as transparent thermoplastic rubber hydrochloride, a sheet of paper, and an orificed relatively rigid body-imparting reinforcing member constructed of a material such as paper board. The fibre board is preferably scored and embossed with strengthening ribs to stiffen such material, especially around openings.

15 As shown in Fig. 1, a blank for the production of the improved container is produced by laminating an orificed sheet of paper 10 to a continuous sheet of transparent rubber hydrochloride 11. A product on the market which may be employed for the inner pellicle is known as 20 "Pliofilm." This thin thermoplastic rubber hydrochloride sheet may be laminated to the paper by application of a suitable adhesive to the latter and then bringing the two webs together 25 under pressure. A suitable laminating adhesive may be produced by dissolving chlorinated rubber in a solvent, or other well known adhesives can be employed as required.

To the resulting laminated sheet is fabricated 30 an external sheet of paper board 12. This paper board is provided with longitudinally extending orifices 13 which provide visibility of the product within the finished container, it being understood that the paper 10 also is orificed to provide 35 openings in registration with the openings 13, as may be seen in Figs. 2 and 3.

The paper board body-imparting reinforcing member 12 is of smaller dimensions than the laminated sheet of paper and Pliofilm to provide 40 relatively large end extensions and relatively short side extensions 14 and 15, respectively.

Preferably, the member 12 is embossed about the openings 13 so as to impart rigidity to the package. Also, the paper board is suitably scored 45 to provide for corner folds.

A first step in the formation of a container from the blanks includes folding the combined rubber hydrochloride, paper, and paper board reinforcing member into the rectangular shape 50 shown in Fig. 4. In this shape the end extensions 13 of the paper and Pliofilm come together in the manner shown in Fig. 2 with the rubber hydrochloride side of these extensions in face-to-face relation. It will be noted that the extensions project beyond the paper board. Next

and pressure are applied to the paper sides of the extensions 14 to cause the inner layers of rubber hydrochloride to become heat-sealed into a unitary longitudinally extending seam. This seam then is folded over in the manner shown in Fig. 3 and adhesively secured to one of the adjacent ends of the paper board reinforcing member on the exterior surface thereof. The resulting combined tube has the shape and construction shown in Fig. 4. The completed longitudinal seam is provided with a continuous Pliofilm-to-Pliofilm contact and extends to the outside of and beyond the paper board reinforcing member. The extended seam is interlocked with the reinforcing member by attachment to its exterior surface to provide a strong construction and protection for the longitudinal seam.

After formation of the tube in this manner, the tube may be flattened along diagonal lines and shipped to a consumer in such condition. When ready for use, the collapsed tube then is squared and one end is formed in the manner shown in Figs. 5 and 6. That is, opposite sides of the extensions 14 are brought together so that the rubber hydrochloride interior layer is in face-to-face relation as shown in Fig. 5. Heat and pressure then are applied to the exterior or paper side of the resulting upwardly extending lip 16 to provide a unitary seal of a liquid-proof nature. In this manner the extensions 14 provide an end closure and the end is completed by refolding the lip 16 over adjacent the end of the container and then folding the extensions 17 over on top of the lip as shown in Fig. 7. The refolded portions then are secured together and secured to the end of the container by the use of a thermoplastic adhesive.

The container then is filled with a liquid and the unclosed end is sealed in the manner shown in Figs. 5 and 6 to complete the formation of the container.

To provide for an intermediate bracing of the container a band 18 is folded about the center of the paper board reinforcing member and its overlapping ends are adhesively or otherwise secured together to provide a continuous reinforcing band.

It will be noted that the structure described is quite simple and easily produced. The contents of the package may be observed through the openings 13 and these openings may be of any desired shape. In some instances changes in the structure and method described heretofore will be found desirable. For instance, the paper layer 10 may be provided by adhesively securing marginal extensions of paper to the paper board body-imparting reinforcing member. This makes it unnecessary to laminate the paper to the interior layer of Pliofilm. The shape of the package will be defined by the reinforcing board 12 and the ends of the container are free from the paper board. This allows access to be gained to the contents of the package as by dropping the container into a funnel containing a sharp instrument which will puncture the end closures. Other types of reinforcing bands may be employed rather than the paper band 18. A metal band may be used for this purpose, or, in some cases it will be desirable to fasten a metallic wire about the center of the package.

The various changes in the composition of materials, structure and procedure described which may be made without departing from the

scope of the invention are intended to be included in the appended claims.

I claim:

1. A container of the type described, comprising an orificed paper board body-imparting member folded into container formation with adjacent edges, paper extensions secured interiorly of said bracing member and passing between the adjacent edges thereof, and a transparent rubber hydrochloride interior pellicle secured to said bracing member and said paper extensions, said paper extensions and rubber hydrochloride pellicle being sealed into an integral longitudinally extending seam exteriorly of and beyond the adjacent edges of said bracing member, and said seam being folded over and interlockingly secured to the exterior face of said bracing member, said paper being centrally orificed to permit inspection of said container contents through the orifices of said paper board body-imparting member and said rubber hydrochloride pellicle.

2. A container having an inner layer of transparent rubber hydrochloride, an intermediate layer of paper and an exterior layer of an orificed paper board bracing member folded into container formation with adjacent longitudinal edges, said paper and rubber hydrochloride extending outwardly and beyond said paper board adjacent said longitudinal edges and adjacent the ends thereof, and said extensions of paper and rubber hydrochloride all being thermally and interlockingly sealed to provide a longitudinal seam exteriorly of said paper board and end sections, said intermediate layer of paper being orificed to coincide with the orifices of said paper board bracing member.

3. A container of the type described, comprising a rectangular reinforcing strip having fold lines defining four panels each having openings therein and the width of said strip being substantially the height of the container, said strip having laminated thereto a sheet of rubber hydrochloride secured to a paper reinforcing sheet, the latter having openings therein and being secured adjacent the reinforcing strip with the rubber hydrochloride sheet forming the inner surface of the container, said laminated sheet being larger than the reinforcing strip and extending beyond the ends thereof and being hermetically sealed and folded to provide end closures for said container free of body flaps, said strip having adjacent free edges being spaced apart and providing a passageway for adjacent edges of the inner laminated sheet extending the free edges of said strip, said sheet being secured marginally where it protrudes from said passageway with the rubber hydrochloride marginal surfaces in face-to-face relationship to form a seam, said seam being folded outwardly alongside one exterior wall of said reinforcing strip and interlockingly secured thereto, and the openings in the paper and the openings in the panel of said reinforcing strip coinciding to provide windows for observation of the contents of said container.

4. A container according to claim 3 having an intermediate bracing member provided for said container in the form of a band folded about substantially the center of the reinforcing strip member and having overlapping end members secured together to provide a continuous reinforcing band.

GEORGE ARLINGTON MOORE.
